Inventor

Charles, D. Whiting

UNITED STATES PATENT OFFICE.

CHARLES D. WHITING, OF CHICAGO, ILLINOIS.

CAR-BRAKE.

SPECIFICATION forming part of Letters Patent No. 286,853, dated October 9, 1883.

Application filed August 9, 1883. (No model.)

To all whom it may concern:

Be it known that I, CHARLES D. WHITING, of Chicago, in the county of Cook and State of Illinois, have invented certain new and useful Improvements in Railway-Car Brakes; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to improvements in that class of car-brakes in which the brake-shoes are applied to the top of the wheel, and has for its object the reduction and simplifying of the parts of which it is constructed.

With these ends in view, my invention consists in the combination of parts that will be fully described in the specification and distinctly pointed out in the claims.

In the accompanying drawings, Figure 1 represents the side view of my brake attached to a passenger-car. Fig. 2 is an end view, showing my brake applied to the wheels on one side of the car; and Fig. 3 is a plan view of the same. Fig. 4 represents my brake attached to a freight-car truck. Fig. 5 shows 30 the manner of applying the brakes simultaneously by means of levers.

In the drawings, D represents the supporting-pieces for the rod A and its attachments, which will be referred to hereinafter. Said supports have at their upper ends enlargements, in which is bored or otherwise formed a hole for the journals of rod A, and at the lower end it is made fast to the journal-box of the car-axles and secured about midway by 40 the straps M.

B B are the shoe-levers, forked at one end and securely fastened on each side of the support D to the rod A, and to which are attached the brake-shoes C C.

E E are arms, also attached to rods A, and which are nearly in an upright position.

Attached to the arms E E are rods F F, which are in turn attached to either end of the pivoted bar or lever G.

H is an arm attached centrally to the arm G, and by which it is oscillated.

To the end of arm H is attached the rod I, that leads to the hand or air brake. When this rod is pulled in direction of the arrow 1, arm H will turn the lever or arm G, to which is attached the rods F F, causing them to turn the rods A, thereby applying the brakes, as distinctly shown in Fig. 5. The weight of the shoes and arms on the rod A being on one side would cause the shoes to be always in contact with the wheels, and cause more or less friction. To counteract this a spring or weight may be attached. I have preferred the latter, and will describe the same. To the end of arm H, and opposite to the rod I, is attached a pivoted bell-crank, K, upon the outer end of which is placed a counter-weight, L. Upon applying the brakes the weight will rise, and upon their release the counter-weight will fall, thereby lifting the shoe clear of the wheels.

It will be evident from the above description, and the views shown in the drawings, that by placing my supports for the brake-rod, and also the rod, on the outside of the wheels, and attaching the supports to the journal-boxes, either outside or inside the truck-frame, I produce a light, strong, efficient, and durable brake, and the working parts of which can be readily inspected, even should the car be moving at a moderate speed.

I am aware that brakes have been applied to the tops of car-wheels; but this I do not claim, broadly; but

What I do claim is—

1. In a car-brake, the combination of brake-rod, its supports, and the shoe-lever, all supported and attached to the journal-box, substantially as shown and described.

2. The combination of rod A, levers B, shoes C, supports D, and the journal-boxes, said supports being attached to the journal-box, substantially as shown and described.

3. The combination of the rod A, lever B, arm E, supports D, said supports being attached to the journal-boxes, rod F, levers G and H, and means for returning the levers when released, substantially as set forth.

CHARLES D. WHITING.
